UNITED STATES PATENT OFFICE.

GROVER C. MOORE, OF CAMPTON, GEORGIA.

RESILIENT WHEEL.

1,087,038.

Specification of Letters Patent. Patented Feb. 10, 1914.

Application filed July 28, 1913. Serial No. 781,674.

To all whom it may concern:

Be it known that I, GROVER C. MOORE, a citizen of the United States, residing at Campton, in the county of Walton and State of Georgia, have invented certain new and useful Improvements in Resilient Wheels; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in resilient wheels and comprises a simple and efficient device of this nature having various details of construction and combinations and arrangements of parts which will be hereinafter fully described, shown in the accompanying drawings and then specifically defined in the appended claim.

My invention is illustrated in the accompanying drawings, in which:

Figure 1 is a side elevation of a wheel made in accordance with my invention. Fig. 2 is a sectional view on line 2-2 of Fig. 1. Fig. 3 is a detail perspective view of one of the resilient spokes. Fig. 4 is a perspective view of the hub showing a drum connected thereto, and Fig. 5 is a face view of one of the hub sections.

Reference now being had to the details of the drawings by letter, A, A designate two rings having inclined flanges A' adapted to clamp the opposite inclined faces C of the solid tire D and said rings are provided with series of lugs A² projecting therefrom at intervals and each is apertured, the lugs arranged in pairs and adapted to receive the bolts E. The spokes are constructed of resilient metal, the outer end of each being turned to form a roll and engaging one of said bolts upon which it has a pivotal connection. The hub is made up of two complementary sections, designated respectively by letters I and K, and each is provided upon its inner face with a series of radial slots L which are preferably triangular in cross section and terminate blindly at their inner ends, while their outer ends have contracted slotted portions N leading through the circumference of the sections. Said hub sections are centrally apertured for the re-

ception of the axle L' and to one of said sections a brake drum M is fixed.

It will be noted that the inner end of each spoke F has an angular projection F' adapted to conform to and seat in one of the angular slots L, each section of the hub receiving half of the angled end and the two sections, when held together by means of bolts P, being adapted to securely hold the inner ends of the spokes solidly upon the hub.

By the provision of a wheel made in accordance with my invention, it will be noted that a simple and efficient device is afforded whereby sufficient resiliency is obtained in the springs to take up the vibrations necessary in running gear of automobiles as well as additional resiliency which is afforded by the rubber tire. By the particular construction shown, the spokes, it will be noted, will be interchangeable as well as the tire, the parts being readily replaced when desired for any purpose.

What I claim to be new is:

A resilient wheel comprising a rim, two disks having central registering apertures and series of registering slots in the adjacent faces of said disks, the inner ends of said slots terminating within slight distances from the marginal edges of said apertures, said slots being substantially V-shaped in cross section and provided with shoulders positioned short distances from the peripheries of the disks, said slots being contracted intermediate the shoulders and the circumferences of the disks with one wall of the contracted part of each slot flush with the wall of the latter, resilient spokes, an elongated lug upon each spoke at one end thereof and having its outer face angled, said lug being adapted to conform to and engage registering slots in the two disks and bearing at its outer end against two of said shoulders, while the shank portion of the spoke passes through the contracted portion of the slots and is held by the opposite parallel walls thereof and engaging the rim at their outer ends, as set forth.

In testimony whereof I hereunto affix my signature in presence of two witnesses.

GROVER C. MOORE.
